US00D927858S

(12) **United States Design Patent** (10) Patent No.: **US D927,858 S**
Zaha (45) Date of Patent: **** Aug. 17, 2021**

(54) SHEET MATERIAL	D221,330 S * 8/1971 Ottinger	D25/150
(71) Applicant: Schattdecor AG , Thansau (DE)	D224,149 S * 7/1972 Sahm	D25/150
(72) Inventor: Christian Zaha , Thansau (DE)	D224,150 S * 7/1972 Sahm	D25/150
(**) Term: 15 Years	D239,295 S * 3/1976 Dougherty	D25/150
(21) Appl. No.: 35/509,157	D242,803 S * 12/1976 Schuss	D25/163
(22) Filed: Apr. 3, 2020	D244,804 S * 6/1977 Kies	D5/53
(80) Hague Agreement Data	D260,311 S * 8/1981 Ford	D25/150
Int. Filing Date: Apr. 3, 2020	D261,189 S * 10/1981 Ford	D25/150
Int. Reg. No.: DM/207263	D261,191 S * 10/1981 Ford	D25/150
Int. Reg. Date: Apr. 3, 2020	4,409,276 A * 10/1983 Martinelli	C09D 5/28 428/142
Int. Reg. Pub. Date: Apr. 24, 2020	D354,358 S * 1/1995 Wells	D25/138
(51) LOC (13) Cl. 05-06	5,869,138 A * 2/1999 Nishibori	B27N 7/005 427/274
(52) U.S. Cl.	6,041,836 A * 3/2000 Murai	B27D 5/00 144/162.1
USPC	D428,500 S * 7/2000 Wederski	D25/150
(58) Field of Classification Search	D622,874 S * 8/2010 Cantley	D25/138
USPC D5/1, 2, 7, 8, 32, 37, 43, 53, 54, 55, 56, D5/57, 59, 61, 62, 99; D19/1, 5; D25/138, 150, 151, 156; D32/40	D644,340 S * 8/2011 Canales	B32B 27/302 D25/138
